GYRAL WHEEL

Daniel A. Nickell, Jr., and Edith Q. Nickell, both of
P.O. Box 1372, Rocky Mount, N.C.

Filed Sept. 16, 1960, Ser. No. 62,169

Term of patent 14 years

(Cl. D34—15)

Figure 1 is a perspective view of a gyral wheel showing our new design;

Figure 2 is a perspective view of the other side of the design for a gyral wheel as illustrated in Figure 1;

Figure 3 is a side elevational view of the gyral wheel shown in Figures 1 and 2;

Figure 4 is a cross-sectional view thereof, Figure 4 being taken substantially on the horizontal plane of line 4-4 of Figure 3, looking in the direction of the arrows; and

Figure 5 is a cross-sectional view thereof, Figure 5 being taken substantially on the vertical plane of line 5-5 of Figure 3, looking in the direction of the arrows.

We claim:

The ornamental design for a gyral wheel, as shown.
